SPRINKLER HEAD ATTACHMENT

Bobby G. Cloud, 7900 Chastain Ave.,
Reseda, Calif. 91335

Filed Dec. 6, 1967, Ser. No. 9,373

Term of patent 14 years

(Cl. D23—7)

The dotted line showing of the sprinkler head in FIGURE 2 is for illustrative purposes only.

I claim:

The ornamental design for a sprinkler head attachment, substantially as shown and described.
